UNITED STATES PATENT OFFICE

168,647

CABINET FOR A RADIO RECEIVER

William F. Fox, Cincinnati, Ohio, assignor to Avco
Manufacturing Corporation, Cincinnati, Ohio,
a corporation of Delaware

Application October 23, 1952, Serial No. 21,955

Term of patent 14 years

(Cl. D56—4)

To all whom it may concern:

Be it known that I, William F. Fox, a citizen of the United States, residing at Cincinnati, in the county of Hamilton and the State of Ohio, have invented a new, original, and ornamental Design for a Cabinet for a Radio Receiver, of which the following is a specification, reference being had to the accompanying drawing, forming a part thereof.

In the drawings:

Fig. 1 is a perspective view of a cabinet for a radio receiver, embodying my new design showing the front, left side and top thereof;

Fig. 2 is a similar view thereof showing the front and left side;

Fig. 3 is a similar view thereof showing the front and right side.

The back of the cabinet is plain.

I claim:

The ornamental design for a cabinet for a radio receiver, as shown and described.

WILLIAM F. FOX.
